1 Claim

ABSTRACT OF THE DISCLOSURE

A low-foaming detergent composition having controlled sudsing capacity which contains as essential components thereof a tertiary amine oxide and a foam-stabilizing agent.

This invention relates to low foaming detergent compositions having controlled sudsing capacity.

It has been acknowledged in the detergent art that in many cases a high production of foam is undesirable, e.g. when using a detergent composition in automatic washing machines. Various so-called low-foaming detergent compositions have been developed in which substances have been incorporated which exerted a foam-depressing action.

It has furthermore been common practice to include foam stabilising agents in detergent compositions to improve the persistence and the stability of the foam produced by agitation of the wash liquors. The prior art compound which function as foam stabilising agents in detergent systems depend upon well-known foam-stabilising functional groups such as the amide, alcolohic, and phenolic hydroxyl groups. Examples of foam stabilising agents are fatty alcohols, fatty acid monoalkanolamides, fatty acid dialkanolamides, p-hydroxyalauphenone and alkylene oxide adducts with a short polyglycol chain such as nonylphenol/4 E.O. These foam stabilising agents do not produce any significant amount of foam themselves, but influence the system in such a way that it becomes less sensitive to soil, so that the foam-depressing action of soil in a wash liquor is decreased.

It has now been found that when using one or more of such foam stabilising agents together with one or more of certain amine oxides, a detergent composition is obtained which not only has a great foam stability, but also a low or at least reduced foaming capacity, i.e. controlled sudsing. This is the more surprising, since the amine oxides in question, examples of which will be given below, have a high foam production, and accordingly it would be expected that, by using such a substance together with a foam stabilising agent, a stabilised high foam level would be obtained. The compositions according to the present invention show, however, a foam level appreciably lower than that of the amine oxides alone.

The amine oxides to be used in the compositions of the invention are known in the prior art and are represented by the formula:

in which R_1 is a branched or straight-chain alkyl radical, containing from 10 to 18 carbon atoms, and R_2 and R_3 are each alkyl radicals containing from 1 to 3 carbon atoms. Examples of these amine oxides are lauryl-, myristyl-, stearyl-dimethylamine oxides. Also mixtures of any of the foregoing compounds may be used according to the present invention.

2

Suitable foam stabilising agents according to the present invention are those mentioned previously. Especially suitable are the fatty acid alkanolamides, such as coconut fatty acid mono- and di-ethanolamides, tallow fatty acid mono-ethanolamide, etc. Also mixtures of any of these foam-stabilisers may be used. The weight ratio of amine oxides to foam stabilising agent is from 25:1 to 1:2. The amine oxides are not included in the term "foam-stabilising agent."

The detergent compositions according to the present invention show their controlled sudsing characteristics over a wide temperature range, viz. from 20° to 90° C., while the water hardness does not influence the foam stability; the foam produced is of a fine texture. They also have excellent detergency characteristics, and are mild in their action towards the skin. The composition may include other constituents, provided its low-sudsing character is not impaired and may naturally contain all the usual constituents desirable in a built detergent composition, such as phosphates, silicates, bleaching agents, whitening agent, perfumes, soil-suspending agents, etc. They may be prepared in any desired physical form, such as powders, pastes, liquids and solids and are suitable for use a dish washing composition, light and heavy duty detergent compositions, hard-surface cleaners and scouring powders.

The present invention is illustrated by the following examples:

EXAMPLE 1

The foaming height of an aqueous solution containing per litre:

2.83 g. of a commercial cetyltrimethylamine oxide known under the trade name Ammonyx CO (equivalent to 1 g. cetyltrimethylamine oxide as dry substance), and 2 g. sodium tripolyphosphate,

was determined in the presence of different amounts of soil by the Ross-Miles test at 45° C., the water hardness being 15° DH (i.e., German hardness). The foaming height was compared with the foaming heights of the solutions obtained by adding to the above solution 0.15 g./l., 0.25 g./l. and 0.5 g./l. of coconut monoethanolamide (CEA).

The results obtained are given in the following table:

Soil, g./l.	Foaming heights in cm. CEA g./l.			
	0	0.15	0.25	0.50
0.....	12.5	4.5	4.0	3.0
1.....	10.0	4.0	4.0	3.0
2.....	7.0	4.0	4.0	3.0
3.....	4.5	4.0	4.0	3.0

The results show clearly that the addition of CEA greatly reduces the foam level and simultaneously improves the foam stability i.e., resistance to the foam reducing action of soil.

The Ross-Miles test is described in "Oil and Soap," May 1941, pages 99-102.

A similar testing procedure was followed in Examples 2-5 and 7-9. In these examples the soil used (if any) was tallow, the solution temperature was 45° C. and the water hardness (unless otherwise stated) was 15° DH. In all cases the diluent in the commercial amine oxides used was water.

EXAMPLE 2

To illustrate the insensitivity of the compositions of the invention to the water hardness, the foaming heights of a 1 litre aqueous solution of a mixture of 1 g. of a commercial tridecyltrimethylamine oxide, known under the

trade name Noxamine C50 (equivalent to 0.52 g. tridecyldimethyl amine oxide as dry substance) and 2 g. sodium tripolyphosphate with and without 0.15 g. coconut monoethanolamide were determined in water of 0° DH and 15° DH. The following results were obtained:

Foaming heights in cm. in water of 0° DH		
CEA added in g./l.		
	0	0.15
Soil, g./l.:		
0.....	15.0	9.0
1.....	13.0	9.0
2.....	10.0	9.0
3.....	9.0	9.0

Foaming heights in cm. in water of 15° DH		
CEA added in g./l.		
	0	0.15
Soil, g./l.:		
0.....	15	8.5
1.....	12	8.5
2.....	9	8.5
3.....	9	8.5

This example clearly shows the insensitivity of the composition according to the present invention to the water hardness with regard to the stability and the reduced level of the foam.

EXAMPLE 3

Three aqueous solutions were prepared each containing 2 g./l. sodium tripolyphosphate (STPP) and 1 g./l. of a different commercial amine oxide, viz. lauryl-, myristyl- and cetyltrimethylamine oxide, as supplied under the trade names Ammonyx LO, MO and CO respectively. The foaming height of each of these combinations was determined with 0 and 1 g. soil per litre. These values were compared with those obtained with the same systems to which 0.15 g. coconut monoethanolamide was added. The following results were obtained:

Foaming height of a solution containing 1 g./l. Ammonyx LO (equivalent to 0.34 g./l. lauryltrimethylamine oxide as dry substance) + 2 g./l. STPP +	CEA in g./l.	
	0	0.15
Soil, g./l.:		
0.....	15.0	6.0
1.....	9.0	9.0
CEA in g./l.		
	0	0.15
Soil, g./l.:		
0.....	15.0	4.5
1.....	5.0	5.5
CEA in g./l.		
	0	0.15
Soil, g./l.:		
0.....	8.5	2.0
1.....	5.0	2.0

These results clearly show a reduced foam level and a great foam stability in respect of the composition of the invention.

EXAMPLE 4

Example 3 was repeated using different foam stabilizers, viz. lauric monoethanolamide (LEA), tallow monoethanolamide (TEA) and coconut diethanolamide

(CDEA). The following results were obtained in the absence of soil:

5	Ammonyx LO						
	LEA, g./l.	TEA, g./l.	CDEA, g./l.	0	0.15	0	0.15
Foam height in cm.....	15.0	7.0	15.0	12.0	15.0	6.5	
Ammonyx MO							
10	LEA, g./l.	TEA, g./l.	CDEA, g./l.	0	0.15	0	0.15
	15.0	4.5	15.0	8.5	15.0	5.5	
Ammonyx CO							
15	LEA, g./l.	TEA, g./l.	CDEA, g./l.	0	0.15	0	0.15
	8.5	2.5	8.5	3	.85	2.5	

These results clearly show the reduction of foam by the addition of different foam stabilizers.

EXAMPLE 5

The foaming height of an aqueous solution containing 2.83 g./l. Ammonyx CO and 2 g./l. STPP was compared with that of the same solution to which 0.15 g./l. nonylphenol condensed with 4 moles ethylene oxide was added. The following results were obtained:

30	Nonylphenol/4 E.O. g./l.	
	0	0.15
Soil, g./l.:		
0.....	12.5	6.0
1.....	10.0	5.5
3.....	4.5	6.0

This example illustrates that the foam stability and foam reduction are maintained by the addition of nonylphenol/4 E.O.

EXAMPLE 6

In a Wyandotte dynamic foam meter (as described in Soap and Chemical Specialties, April 1961, pages 55-57, 104) the foam capacity of aqueous solutions containing 2.83 g./l. of Ammonyx CO equivalent to 1 g./l. of cetyl dimethyl amine oxide as dry substance or 3.21 g./l. of Ammonyx SO (equivalent to 1 g./l. stearyl dimethyl amine oxide as dry substance) and 2 g./l. STPP with and without 0.25 g./l. CEA was determined. 200 ml./min. of solution was used (water hardness 15° DH). The warming-up time was 34 minutes. The following results were obtained:

50	Foam height in mm.		
	Cetyltrimethylamine oxide plus CEA, g./l.....	0	0.25
Temperature:			
55	25.....	30	40
	30.....	35	45
	40.....	150	55
	50.....	300	50
	60.....	470	50
	70.....	585	50
	80.....	>700	60
	90.....	>700	120
60 Stearyltrimethylamine oxide plus CEA, g./l.....			
	Temperature:	0	0.15
	25.....	35	60
	30.....	40	60
	40.....	40	50
	50.....	40	20
	60.....	145	25
65	70.....	260	50
	80.....	350	120
	90.....	380	310

These results illustrate the foam stability and reduced foam over a wide temperature range of the compositions of the invention.

EXAMPLE 7

The foaming height of an aqueous solution containing 3.33 g./l. of a commercial branched tridecyldimethyl amine oxide (supplied under the code name CWA 40-29

ex Union Carbide Cy.) equivalent to 1 g./l. of tridecyldimethyl amine oxide as dry substance and 2 g./l. of STPP was compared with that of the same solution to which 0.25 g./l. of CEA was added.

g. of cetyl alcohol was compared with that of the same solution from which the cetyl alcohol was left out.

	CEA, g./l.	
	0	0.25
Soil, g./l.:		
0.....	18.5	14.0
1.....	15.0	12.5
3.....	12.5	13.0

EXAMPLE 8

The foaming height of an aqueous solution containing per litre a mixture of 1.57 g. of Ammonyx MO (equivalent to 0.5 g. myristyldimethyl amine oxide as a dry substance) and 1.6 g. of Ammonyx SO (equivalent to 0.5 g. stearyldimethyl amine oxide as dry substance) and 2 g. of STPP was compared with the foaming height of the same solution to which 0.25 or 0.5 g./l. of a mixture of coconut monoethanolamide and tallow monoethanolamide (ratio of 1:1) were added.

	CEA plus TEA, g./l.		
	0	0.25	0.5
Soil, g./l.:			
0.....	14.5	5.0	4.0
1.....	9.0	5.0	4.0
3.....	6.0	4.0	4.0

EXAMPLE 9

The foaming height of an aqueous solution containing per litre 2.83 g. of Ammonyx CO, 2 g. of STPP and 0.25

⁴⁰ 0.25 137; 424—70

5	Cetyl alcohol	
	0	0.25
Soil, g./l.:		
0.....	12.5	4.0
1.....	10	3.5
3.....	4.5	3.5

10 What is claimed is:

1. A low-foaming detergent composition having controlled sudsing capacity consisting essentially of an amine oxide, as the only active organic detergent component, of the formula:

20 in which R_1 is an unsubstituted alkyl radical containing from 10 to 18 carbon atoms and R_2 and R_3 are unsubstituted alkyl radicals containing from 1 to 3 carbon atoms; and cetyl alcohol as a foam-stabilizing agent; the weight ratio of amine oxide to the cetyl alcohol foam-stabilizing agent being from 25:1 to 1:2.
